UNITED STATES PATENT OFFICE.

FRANK L. FURBUSH, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

MOIST-AIR FLUE FOR DRYING MACHINES.

Application filed October 31, 1927. Serial No. 229,861.

This invention relates to that type of drying machine, usually employed for drying wool and other textile materials, in which the machine is divided up into compartments, each one having fans or blowers for circulating the air in that compartment and a moist air flue, which, heretofore, also had a blower for forcing a part of the moist air out through that flue. I find in practice that these two sets of blowers are operating against each other as the machine has been constructed heretofore and consequently there is a loss of efficiency. In this machine, heretofore, the moist air flue has been on the side opposite the circulating blower or blowers.

For the purpose of reducing this loss of efficiency I place the moist air flue or box on the same side as the blowers and arrange the moist air box or flue so that the amount of air entering it can be regulated from the outside and also so that the moist air can be led into it from either one of two adjacent compartments and so that the blower heretofore employed for this flue is entirely eliminated and yet the moist air is discharged efficiently.

Other objects and advantages of the invention will appear hereinafter.

Reference is to be had to the accompanying drawings in which

Fig. 1 is a plan of a part of a dryer with the top removed showing the present improvements applied thereto;

Fig. 2 is a sectional view on the line 2—2 of Fig. 1;

Fig. 3 is a longitudinal sectional view on the line 3—3 of Fig. 1, and

Fig. 4 is a perspective view of the exhaust air flue with some adjacent parts illustrated.

As shown, I have applied this invention to a dryer 10 having an apron 11 extending along through it but having partition walls 12 extending across the apron both above and below, if desired, to divide it up into compartments which, except for the openings where the apron passes through, are entirely separate from each other. Each one may be considered as constituting a separate dryer for different parts of the material.

The stock fed to the apron at the end 13 passes continuously through to the end 14

where it is dropped. In each compartment 55 are blowers 15 for circulating the air in the direction indicated by the arrows in Fig. 2 through the steam coils 16 which are usually employed, over on the stock on the apron 11, and then back again. 60

The exhaust moist air flue has usually been on the outside of the dryer opposite the coils 16. It is on this side that the fresh air inlets 17 are located at intervals along the wall of the dryer. I now place the exhaust air flue or air box 20 on the side on which the coils are located and in fact between the ends of two adjacent sets of coils and in registration with the partition 12. That is, where there is one of these partitions there is also an air box at its end. This air box itself constitutes a partition to separate air in one compartment from the next one. 70

Two doors or gates 21, are each operated 75 by a handle 22 at the side and each independently operable. Therefore, either one can be opened, or two can be opened to different degrees, so as to exhaust the air from either compartment or to exhaust different 80 proportions of the moist air from each. Of course, the first compartment is what we call the wet end of the machine. The air is comparatively wet and as it passes through the blower each compartment becomes dryer 85 and dryer with the changing condition of the stock.

This air box takes a portion of the moist air out after passing through the wet stock and is provided with a damper 23 to further regulate the efficiency of the air box 90 as an exhaust flue. It is not desired to circulate all the air around the dryer once and then discard it. Much of it is reheated and used over and over again. 95

It is forced out through the blower by the same blower or blowers and circulates the heated air through the wet stock. If it is found that it is necessary to take more moist air out of the wet end of the dryer 100 than out of the next compartment, the hinged door 21 connected with the wet end compartment can be opened wide and the door of the next compartment can be closed or opened only a little. In the second and 105 third compartments the stock necessarily becomes dryer and less air should be exhausted

from these compartments. This is all provided for by the regulation described.

Although I have illustrated and described only a single form of the invention I am aware of the fact that modifications can be made therein by any person skilled in the art without departing from the scope of the invention as expressed in the claims. Therefore, I do not wish to be limited in these respects, but what I do claim is:—

1. In a dryer, the combination with an endless apron for conveying the material throughout the length of the machine and a series of partitions for dividing the dryer into a plurality of compartments, of blowing means at one side for circulating the air down through the material on the apron, a series of heating coils in each compartment on the same side as the blowing means through which the air is circulated thereby and a moist air box located between each two adjacent sets of coils for receiving the air directly from the bottom of the dryer

below the coils and exhausting it into the open air.

2. In a dryer, the combination with a casing having an endless apron therein for conveying material longitudinally therethrough and provided with a series of partitions dividing it into separate compartments, of blowers circulating the air through the material on the apron, a steam coil in each compartment through which the air is circulated by the blowers and a moist air box at the end of each partition located at the end of the two adjacent coils extending to the bottom of the dryer and above its top, two doors at the bottom of each moist air box and at opposite sides of the same for admitting moist air from either one of the two adjacent compartments and means for adjusting these doors independently of each other.

In testimony whereof I have hereunto affixed my signature.

FRANK L. FURBUSH.
